AUTOMATIC HYDRAULIC VALVE FOR
WATER HEATING SYSTEMS

James T. Barrow, New York, N. Y.

Application August 23, 1935, Serial No. 37,445

7 Claims. (Cl. 236—1)

My invention relates to automatic hydraulic valves for water heating systems and has particular reference to such valves as applied to my water heating system disclosed in my United States Patent No. 1,958,736.

In my hot water system there are two pipes extending from a supplementary water heating element in the furnace of a boiler to a double two-way valve (or valves). In one position this 10 valve connects these two pipes with a hot water tank and hot water piping in the house, in the other position the valve connects these pipes with the boiler. The first position is required when temperature of water in the tank falls below a 15 certain desired limit, and the second position is used when temperature of the water has reached that limit.

The object of my present invention is to provide a valve and valve controlling mechanism 20 which will automatically change the connections between the pipes as described above in accordance with the temperature of the water in the tank.

Another object of my invention is to provide a 25 hydraulic motor for operating the above described valve, the necessary power being supplied by the pressure of water in ordinary water pipes in the house.

Another object of my invention is to provide 30 magnets for operating auxiliary valves controlling the above hydraulic motor, these magnets being in turn controlled by a suitable thermostatic device adapted to close the electric circuit for these magnets when temperature of water in the tank and house piping falls below a 35 desired limit, there being several such thermostatic devices on the market.

For practical purposes I have found that a 40 convenient embodiment of my invention is represented by a cylindrical slide valve with two ports on one side for the pipes from the auxiliary water heating element, and four pipes on the other side, two from the boiler and two from the tank. I connect the sliding portion of this valve with 45 a plunger of a hydraulic cylinder which is moved out placing the valve in the first position when water under pressure is admitted into the cylinder.

I also provide a yieldable resilient means for 50 returning the valve into the second position.

Still another object of my invention is to provide a locking means for holding the valve in the first position while water under pressure is 55 drained out from the cylinder, the latter being

automatically disconnected from the source of such water under pressure.

These and other important features of my invention are more particularly described in the accompanying specification and drawing in 5 which—

Fig. 1 is a sectional elevation of my valve and its operating mechanism, the valve being shown in the first position, Fig. 2 is a similar view showing the valve in the second position, Fig. 3 10 is a diagrammatic view of a boiler and piping including my valve, and Fig. 4 is a sectional view taken on the line 4—4 of Fig. 1.

My valve consists of a cylindrical housing 1 closed with a plug 2 at the rear end and a wall 15 3 at the front end, this wall being also a back wall of a hydraulic cylinder 4 which may be of a larger diameter than the housing 1 of the valve.

The valve has intake ports 5, 6, 7 and 8, and exhaust ports 9, 10, 11 and 12. The ports 5 and 20 9, 6 and 10, 7 and 11, and 8 and 12, are in the same planes, and may be located apposite each other as shown in the drawing. The ports 5 and 6 are connected together by a chamber 13 formed in a box 14 attached to the wall of the 25 valve housing. An intake pipe 15 extends from the chamber 13 to one side of a water heating element 16 in the furnace of a boiler 17. A similar chamber 18 is formed in the other side of the box 14 and is connected by a pipe 19 with the 30 other side of the heating element 16. The exhaust ports 9 and 11 are connected by pipes 20 and 21 with the boiler 17, and the ports 10 and 12 are connected by pipes 22 and 23 with a hot 35 water tank and extend further for supplying hot water for household needs.

A cylindrical valve 24 is slidably fitted in the housing 1 and is provided with two grooves 25 and 26 adapted to connect together ports lying in the same plane. In the extreme front (right 40 as shown) position the groove 25 connects together the ports 6 and 10, and the groove 26 connects the ports 8 and 12, the other ports being closed. In the extreme rear (left) position the other two pairs of ports are connected together, as shown in Fig. 2. The valve 24 has a central longitudinal aperture or bore 27 threaded at the front end into which the end of a rod 28 is fitted. Angular holes 28' extend from the 45 bore 27 to the front end of the valve. The bore 27 and holes 28' serve to equalize the air pressure at both ends of the valve so as not to impede its movements. This arrangement is especially important if a certain amount of wa- 50 55

ter leaks from the pipes into the end spaces in the housing.

The rod 28 has a shoulder 30 against which rests a washer 31 of a piston 32 made preferably of a cup-shaped piece of leather. Washers 33 and 34 rest against the other side of the leather. A tube or sleeve 35 rests with one end against the washer 34, the other end abutting a disc 36. A nut 37 on the end of the rod 28 clamps the disc, sleeve and washers 33 and 34, together with the leather 32 and washer 31 against the shoulder 30.

A metal tubular cover 38 is fitted over the front end of the cylinder 4 and is provided with slots 39 and 40 for arms 41 and 42 extending from valves 43 and 44. The valve 43 is placed in an intake pipe 45 connected with the rear end of the cylinder 4, and the valve 44 is placed in an exhaust pipe 46 also connected with the rear end of the cylinder 4. The valves are made so that the valve 43 is closed when its arm 41 is turned to the right by the disc 36 in its extreme front position, and the valve 44 is opened by the disc 36 in its extreme front position (right as shown in Fig. 1). Washers 47 and 48 limit the movement of the sliding valve 24 and the piston 32. A compression spring 49 tends to move the valve 24 in its front position, hereinafter called first position, and a fluid under pressure, acting on the piston 32 against the pressure of the spring 49, moves the valve member 24 in its front position hereinafter called second position. A spring 50 pulls the arm 41 to the front thereby closing the valve 43. A magnet plunger 51 is connected to the arm 41 on the other side and is acted upon by a core 52 of a magnet 53. The winding of this magnet is connected by leads 54 with the switch of a thermostatic circuit closing device 55 connected with the pipe 22 so as to be affected by the temperature of hot water circulating through this pipe.

A spring 56 tends to close the valve 44. The pipe 45 is connected with a source of compressed fluid (not shown), and the pipe 46 is connected with a drain (not shown) for permitting the fluid from the cylinder 4 to escape.

The disc 36 has an opening 57 for a latch 58 pivotally supported at 59 on the front wall of the cover 38. A compression spring 60 tends to push the latch down thereby releasing the edge of the disc 36 from engagement with the hooked end of the latch. A magnet 61 exerts a pull on an armature 62 on the latch thereby pulling it up against the tension of the spring 60. The magnet is connected with the switch 55. The latter is connected by leads 63 with a source of electric current (not shown). The thermostatic element of the switch 55 has a handle 64 which can be manually set against any temperature upon reaching which by the water in the pipe 22 the switch 60 opens the circuit for the magnet 53 through the leads 54 and for the magnet 61 through its leads 65. The temperatures for convenience are indicated on a scale 66 of the device.

The operation of my device is as follows. If the power line 63 is disconnected, the spring 50 closes the valve 43, as shown in Fig. 1. The piston 32 remains in its closed or rear position being held by the spring 49. The valve member 24 remains in its first position as shown in Fig. 2. The intake pipes 15 and 19, leading from the water heating element 16, remain connected to the first group of the exhaust pipes 20 and 21 extending to the boiler. The apparatus retains the same position if the switch 55 is connected

with the electric current, but the temperature of the water in the pipe 22 equals or exceeds the temperature for which the index 64 is set.

The spring 60 presses the latch 58 down with its back side against the edge of the opening 57, so that the latch does not offer any resistance to the movement of the piston in either direction.

If temperature of water in the pipe 22 drops below that for which the index hand 64 is set, the switch 55 closes the circuit for the magnets 53 and 61. The plunger 51 becomes attracted by the magnet 53 and turns the valve 43 into open position as shown in Fig. 2. The magnet 61 pulls the armature 62 and with it the latch 58 up, pressing its end tapering portion against the upper edge of the opening 57. The valve 44 remains closed. The valve 43 being now open, the compressed fluid will flow through the pipe 45 into the cylinder 4 forcing the piston 32 outward. This motion will continue until the valve member 24 comes to rest against the washer 47. In this position the disc 36 will pass beyond the notch on the latch 58, so that the latch under the pull of the magnet 61 will engage the edge of the opening 57 thereby locking the disc 36 and with it the piston and the valve member 24 in the second position, as shown in Fig. 1. The force of the compressed fluid behind the piston will turn the arm 41 against the tension of the spring 50 thereby closing the valve 43 as shown in Fig. 1. At the same time the disc 36 will turn the arm 42 to the right opening the exhaust valve 44. Consequently the fluid from the cylinder 4 will escape through the pipe 46 into the drains. The pipe 46 and its valve are of sufficient size to permit air to enter the cylinder in place of the escaped fluid. The apparatus will remain in this position, with the heating element 16 connected with the tank 29 through the pipes 15, 19, 22 and 23, until the water in the tank and pipe 22 is heated to the degree indicated on the switch 55.

As soon as the water in the tank and pipe 22 reaches the predetermined temperature for which the thermostatic device is set, the switch in it will disconnect the current from the magnets 53 and 61. The spring 60 accordingly will push the latch 58 down releasing the disc 36. The piston and the valve member 24 will be then free to move back into the first position, the cylinder being empty. Upon completion of this movement the tank and pipes 22 and 23 will become disconnected from the water heating element 16, and the latter will be connected to the boiler through the pipes 20 and 21. The valves 43 and 44 will remain closed under action of the springs 50 and 56. The system will remain in this position until temperature of water drops and the magnets 53 and 61 become energized.

It is understood that my apparatus can be used with any system in which pipe connections must be changed in accordance with the rise or fall of temperature at a point of its control.

It is also understood that the preferred embodiment of my invention as described can be modified without departing from the scope of my invention as recited in the appended claims.

I claim as my invention:

1. In an automatic hydraulic valve, the combination of a cylindrical housing provided with intake and exhaust ports, a set of intake pipes connected with said intake ports, two sets of exhaust pipes connected with respective exhaust ports, a valve member slidably fitted in said housing and adapted in one position to connect said

- intake pipes with the first set of said exhaust pipes and in the second position to connect said intake pipes with the second set of said exhaust pipes, a cylinder, a piston in said cylinder operatively connected with said valve member, intake and exhaust pipes connected with said cylinder, said intake cylinder pipe being adapted to deliver a compressed fluid for moving said piston into the second position, a spring adapted to return 5 said piston into the first position when there is no fluid in said cylinder, valves in said cylinder pipes, springs tending to close said valves, means to close said cylinder intake valve by said piston in its second position, means to open said cylinder 10 exhaust valve by said piston in its second position, means to releasably lock said piston in the second position, an electromagnetic means for rendering said locking means operative, an electromagnetic means for opening said cylinder intake valve against the tension of its spring, and means to control both of said electromagnetic means by the temperature of a fluid passing through said valve member.
2. In an automatic hydraulic valve, the combination of a cylindrical housing provided with intake and exhaust ports, a set of intake pipes connected with said intake ports, two sets of exhaust pipes connected with respective exhaust ports, a valve member slidably fitted in said housing and adapted in one position to connect said intake pipes with the first set of said exhaust pipes, and in the second position to connect said intake pipes with the second set of said exhaust pipes, a hydraulic cylinder, a piston in said cylinder operatively connected with said valve member, intake and exhaust pipes connected with the rear end of said cylinder, valves in said cylinder pipes, said intake pipe being adapted to deliver compressed fluid into said cylinder thereby causing said piston with said valve member to move into said second position, a spring adapted to return said piston and said valve member into said first position, means to close said cylinder intake valve and to open said cylinder exhaust valve by said piston in its second position, electromagnetic means for rendering said locking means operative, electromagnetic means for opening said cylinder intake valve when said piston is in its first position, and a 30 thermostatic switch subjected to the temperature of water in said second set of pipes and connected with a source of electric current, said switch being adapted to energize said electromagnetic means when the temperature of said water falls below a predetermined limit.
3. In an automatic hydraulic valve, the combination of a valve member having two operative positions, a hydraulic cylinder, a piston in said cylinder operatively connected with said valve member, intake and exhaust pipes for a compressed fluid connected with said cylinder, said piston when moved by said compressed fluid being adapted to place said valve in its second position, valves in said pipes, means to return said piston into said cylinder thereby placing said valve member in its first position, when said intake valve is closed and said exhaust valve is opened, means to close said intake valve and to open said exhaust valve by said cylinder in said second position, springs tending to close said cylinder valves, electromagnetic means for opening said intake valve against the tension of its spring, means to releasably lock said piston in its second position, an electromagnetic means for rendering 45
- said locking means operative, and means to control both of said electromagnetic means by the temperature of a fluid passing through said valve member.
4. In an automatic hydraulic valve, the combination of a valve member having two operative positions, a cylinder, a piston in said cylinder operatively connected with said valve member, intake and exhaust pipes connected with said cylinder, said intake pipe being adapted to deliver a compressed fluid into said cylinder thereby moving said piston with said valve into a second position, valves on said pipes, springs tending to close said valves, means to close said intake valve and to open said exhaust valve by said piston in its second position, a latch adapted to lock said piston in said second position, a spring adapted to render said latch inoperative, an electromagnetic means for rendering said latch operative against the tension of its spring, an electromagnetic means adapted to open said cylinder intake valve against the tension of its spring and when not held by said piston, means to return said piston into the first position, and means to control both of said electromagnetic means by the temperature of a fluid controlled by said valve member.
5. In an automatic hydraulic valve, the combination of a valve member having two operative positions, a cylinder, a piston in said cylinder operatively connected with said valve member, intake and exhaust pipes connected with said cylinder, said intake pipe being adapted to deliver a fluid under compression into said cylinder thereby moving said piston into a second position of said valve member, valves in said pipes, springs tending to keep said valves closed, arms on said cylinder valves, an extension on said piston engaged by said arms, said extension being adapted to close said intake valve and to open 50 said exhaust valve when said piston is in the second position, means to releasably lock said extension with said piston in the second position, an electromagnetic means for rendering said locking means operative, an electromagnetic means for opening said intake valve when said piston is in the first position, a yieldable means for returning said piston into the first position when there is no fluid in said cylinder, and means to control both of said electromagnetic means by the temperature of a fluid controlled by said valve member.
6. In an automatic hydraulic valve, the combination of a valve member having two operative positions, a hydraulic motor operatively connected with said valve and having two operative positions corresponding to said valve positions, intake and exhaust pipes connected with said motor, said intake pipe being adapted to deliver compressed fluid to said motor for moving it into 60 the second position, valves in said pipes, springs adapted to close said valves, said intake valve being adapted to be closed and said exhaust valve being adapted to be opened by said motor in its second position, means to releasably lock said motor in the second position, an electromagnetic means to render said locking means operative, means to render said locking means inoperative when said electromagnetic means is inoperative, a yieldable means to return said motor into the 65 first position, an electromagnetic means to open said intake valve, and a thermostatic switch adapted to control said electromagnetic means by the temperature of a fluid passing through said valve member.

7. In an automatic hydraulic valve, the combination of a valve member having two operative positions, a hydraulic motor operatively connected with said valve and having two operative 5 positions corresponding to said valve positions, intake and exhaust pipes connected with said motor, the intake pipe being adapted to deliver compressed fluid to said motor for moving it into the second of said positions, valves in said pipes, 10 retrieving means for closing said pipe valves, said intake valve being adapted to be closed and said

exhaust valve being adapted to be opened by the motor in its second position, electromagnetic means controlling the opening of said intake pipe valve, means to open said exhaust valve by the motor in its second position, a thermostatic 5 switch for said electromagnetic means adapted to be controlled by the temperature of a fluid passing through said valve member, and means for retrieving the motor into the first position.
